UNITED STATES PATENT OFFICE.

THOMAS A. KILLMAN AND JOHN R. STARK, OF NASHVILLE, TENNESSEE.

FOLDING BED.

1,087,497.

Specification of Letters Patent. Patented Feb. 17, 1914.

Application filed March 17, 1913. Serial No. 754,899.

To all whom it may concern:

Be it known that we, THOMAS A. KILLMAN and JOHN R. STARK, citizens of the United States, residing at Nashville, in the county of Davidson and State of Tennessee, have invented certain new and useful Improvements in Folding Beds, of which the following is a specification.

This invention relates to folding beds, and has for one object the provision of a bed in which the head section is perfectly balanced at all times and the bed may be adjusted to different positions by the person occupying the same.

15 A further object of the invention is to provide a bed having a head-board which may be utilized as a table or tray.

20 A further object of the invention is to improve, generally, the construction and arrangement of parts of a folding bed to the end that the efficiency of the same may be increased, and the invention consists in certain novel features which will be herein-after first fully described and then more 25 particularly pointed out in the appended claims.

In the accompanying drawings which illustrate what is now believed to be the best embodiment of the invention: Figure 1 30 is a perspective view of the bed extended to support a person in a sleeping or horizontal position; Fig. 2 is a side elevation showing the parts adjusted to support the occupant in a sitting position; Fig. 3 is a 35 side elevation showing the bed folded as it appears when not in use; Figs. 4 and 5 are detail sectional elevations of the track or support for the foot end of the spring frame or mattress; Fig. 6 is a detail perspective 40 view of the head-board.

In carrying out our invention, we employ a foundation or main supporting frame consisting of a pair of posts 1 connected by upper and lower cross bars 2 and a second 45 pair of posts 3 which are somewhat taller than the posts 1 and are connected by cross bars 4 and 5 disposed near their lower ends and at intermediate points of their heights, the said cross bars 4 and 5 being disposed 50 in the same horizontal planes as the upper and lower cross bars 2, respectively, as will be readily understood. These pairs of posts are connected by upper and lower side bars 6 and are equipped with casters or rollers 55 7 so that the apparatus may be readily moved from point to point within a room.

These several posts and cross bars are constructed of metal to obtain the maximum strength with the minimum weight and size, and the upper cross and side bars as well 60 as the posts are constructed of channel iron for the same reason.

Pivoted to the upper ends of the posts 3 are the upper side bars 8 of the head frame and the lower side bars 9 of the head frame 65 are likewise pivoted to the posts 3 near the lower ends thereof, these side bars 8 and 9 extending from the said posts and having their outer ends pivoted to supplemental legs or supports 10, which supplemental 70 legs or supports are connected by cross bars 11 so that the structure will be rigid when in use. Pivoted to the posts 1 and extending away from the same are the upper side bars 12 and the lower side bars 13 which 75 constitute the main portions of the foot frame of the bed and have their outer ends pivoted to the supplemental legs or supports 14 which are connected by cross bars 15 in the same manner and for the same 80 reason that the supplemental legs 10 are connected by the cross bars 11. The lower side bars 13 of the foot frame are extended inwardly beyond the posts 1 and are provided at their extremities in their upper 85 edges with notches 16 which are adapted to engage pins or studs 17 on the lower side bars 6 of the foundation frame for a purpose which will be presently set forth. Rigid with the upper cross bar 15 and the 90 upper side bars 12 is a foot plate 18 which is disposed at a right angle to the said side bars 12 and secured to the said foot plate and the said side bars are the inclined channel irons or tracks 19 which constitute 95 supports and guides for the end of the spring or mattress frame. The inner ends of the upper side bars 8 of the head frame also form a part of the spring frame and are connected by links or intermediate bars 100 20 with the side bars 21 forming the foot portion of the spring or mattress frame, the said links or connecting bars 20 having their opposite ends pivoted to the ends of the side bars 8 and 21, respectively. The outer ends 105 of the side bars 21 are connected by a cross bar 22 and upon the said cross bar 22, we secure a bracket or stop 23 which prevents the mattress or other bedding slipping off the foot end of the bed.

110 The side bars 8, 20 and 21 with the cross bars 22 and the upper cross bars 11 con-

stitute the frame for the bed bottom 24 which may be of any desired form and is illustrated as consisting of intersecting wires or links and springs connecting the outermost wires or links with the sides and ends of the frame. The inner ends of the lower side bars 9 of the head frame are pivoted to pitmen or levers 25 which extend upwardly and rearwardly therefrom and have their upper ends pivoted to the intermediate bars 20, as indicated at 26, adjacent the rear ends of the same. Pivoted to and rising from the said pitmen or levers 25, near the connection of the said levers with the side bars 9 at each side of the bed, are locking bars 27 which are rigidly connected by a cross bar or rod 28 and are provided with notches 29 in their edges adapted to engage pins or studs 30 on the upper side bars 6 of the main or foundation frame. The said bars 27 are provided with handles 31 at their upper ends so that they may be easily reached by a person occupying the bed.

Studs 32 are provided on the upper side bars 6 so as to prevent the locking bars being moved to too great an extent away from the studs 30 and proper engagement of the bars with the said studs in any set position is thereby assured. Coiled springs 33 are secured to the upper cross bar 5 and to the lower cross bar 11 and relieve the occupant of the bed from the necessity of exerting much force in raising the head frame, the tension of the springs being greatest in the lowest position of the frame and gradually decreasing as the frame rises and in any position is just sufficient to balance the weight of the frame.

The head-board 34 is normally over the upper cross bar 11 of the head frame, but is not secured rigidly thereto. Lever arms 35 are pivoted to the upper side bars 8 of the head frame and at their outer ends carry a pivot rod 36 which passes through bearings or brackets 37 provided therefor on the inner side of the head-board above the center of the same so that, if the said lever arms be swung about their pivotal points 38, the head-board will swing inwardly between the said lever arms and be engaged and supported by the small brackets or stops 39 on the said arms. The inner ends of the lever arms are extended beyond their pivots and are provided with notches 39' adapted to engage studs or pins 40 on the lower side bars 9 of the head frame so that, if the head-board be swung over in front of the bed bottom as shown in Fig. 2, the studs 40 by their engagement with the notches 39' will support the head-board in the position to which it has been moved so that it may be used as a tray or reading or writing table. To prevent the head-board swinging inwardly over the bed bottom when the bed is to be used for sleeping purposes, clips or

brackets 41 are secured to the lower edges of the head-board and are adapted to engage the upper cross bar 11, while a button 42 is pivoted upon the said cross bar in position to extend over the head-board and hold it against movement beyond the cross bar.

The outer extremity of the foot portion of the bed bottom is equipped with rollers 43 which ride upon the tracks or guides 19 and thereby permit the said foot portion of the bed bottom to move easily and readily and will support the said portion of the bed in any position to which it may be adjusted.

It is thought the uses of the improved bed will be readily understood from the foregoing description, taken in connection with the accompanying drawings.

When the several parts are extended, as shown in Fig. 1, the apparatus may be utilized as an ordinary bed. If the person occupying the bed desires to assume a more upright position, he merely releases the locking bars from their engagement with the studs 30 and holds them disengaged with a slight downward pressure, while he assumes the desired position, subsequently reengaging the locking bars with the studs to maintain the adjustment. It does not make any difference whether the person occupying the bed is one of light weight or heavy weight, he is so perfectly balanced in all positions or angles that he can raise himself from a horizontal or sleeping position up to a perpendicular position or sitting posture with practically no effort on his part, the action being very similar to that of rocking in a well balanced rocking chair.

It will be noticed that the head portion of the spring frame 8 is pivoted at 49 to the upper extremities of the extended posts 3 of the main frame so that the frame 8 is free to turn on the bearings or pivotal points 49; also that the lower bar 9 is pivoted at 50 to the same upright posts 3 of the main frame as the bar 8 above; also that the extreme right-hand ends of the bars 8 and 9 are connected to the upright posts 10. It will also be noticed that the bars 8 and 9 extend a distance to the left of the upright posts 3 of the main frame to pivotal points 47 and 48 where the bar 8 connects at 47 to one end of the side bar 20 which forms the middle or seat section of the spring frame. The left-hand end of the bar 20 is connected at 26 and is supported by a pitman bar 25 which extends downward and rearward and is connected at 48 to the extended portion of the lower bar 9. Now it is evident that if weight be placed on the left-hand end of the bar 8 (which is a side bar of the head section of the spring frame) or if weight be placed on the middle or seat section 20 of the spring frame it will have a tendency to cause the left-hand ends 47 and 48 of the bars 8 and 9 to move downward and with

them the middle or seat section 20 of the spring frame and thereby cause the right-hand ends of the bars 8 and 9, or, in other words, the head section of the bed to move upward. However, if a sufficient weight be placed on the right-hand end of the bar 8 or head section to counterbalance the weight on the middle or seat section then the whole system of frames and bars, together with the weight will become balanced on the pivotal points 49 and 50 and will have no tendency to move in either direction. But, if the least pressure be applied in either direction the head portion of the bed will move up or down according to the direction in which the pressure is applied, the whole turning on the pivotal points 49 and 50. Now this is exactly the condition that exists when a person occupies the bed. His head, shoulders and chest rest on the head section 8 or that portion to the right of the pivotal points 49 and 50, while his hips rest on the middle or seat section 20 and his legs and feet on the foot section 21, so that, when occupying a normal position on the bed his weight is so distributed on the right and left hand sides of the pivotal points 49 and 50 that he becomes perfectly balanced on said points and on the slightest effort to rise after releasing the rods 27 the head portion of the bed will rise with him to any position from a horizontal or reclining position up to an upright or sitting posture so that it requires scarcely any effort on his part to rise up and sit up in the bed or lie down again, the whole action, as stated above, being very similar to that of rocking in a nicely balanced rocking chair.

The distance between the pivotal connection of the upper side bars 8 with the posts 3 and the connection between said side bars and the bars 20 is greater than the distance between the pivots of the lower bars 9 and the connection of the same with the pitmen or levers 25, so that, when the head portion of the bed is raised, the inner ends of the bars 8 will describe a greater arc and move a greater distance than the inner ends of the lower bars 9, the result being that the bars 20 and 21 are drawn toward the head end of the bed and as the levers 25 are not extensible nor collapsible they will, as they follow the movement of the lower bars 9, exert a lifting force upon the rear ends of the connecting bars 20 so that said ends will be raised and the bars 20 and 21 will assume inclined positions, as clearly shown in Fig. 2. In Fig. 2, the parts are shown adjusted to permit the occupant to assume a natural sitting position. The head-board may be easily disengaged from the head frame by an attendant before the head frame is raised and the lever arms 35 then swung around so that the head-board will be supported in front of the head portion of the mattress or

bed bottom and in front of the occupant. It will be noted that any tendency of the main frame to tip over toward the head end of the bed when the parts are adjusted as shown in Fig. 2 will be counteracted by the weight of the foot portion of the bed and the greater leverage exerted by the same in its extended position, so that the bed may be used without any fear of accident, the studs 17 and notches 16 holding the foot portion to the main frame in such a manner that the main frame cannot tilt without raising the foot frame.

When the bed is not in use and it is desired to fold the same into a small compass, the side bars 8 and 9 are swung upon their pivotal connections with the posts 3 so as to assume positions approximafely in the vertical plane of said posts, as shown in Fig. 3, and the foot portion of the bed is then swung upwardly toward the head portion, the side bars 21 and the cross bar connecting the outer ends of the same being first swung upwardly upon their pivotal connections with the intermediate bars 20 so as to assume a position above the said intermediate bars. The upward movement of the foot portion of the frame will cause the side bars 12 and 13 and the supplemental legs 14 to fold together into the vertical plane of the posts 1, as will be readily understood from Fig. 3, and the foot plate or board 18 will extend over and meet the head-board 34, as shown. The foot-plate 18 and the head-board 34 will thus effect a complete closure for the top of the folded structure which may then be utilized as a stool or may be set aside out of the way, as may be preferred. To prevent the opening of the folded structure, latches 44 are hung upon the ends of the foot-plate 18 and are adapted to engage studs 45 on the edges of the head-board, as shown in Fig. 3 and as will be readily understood.

It will thus be seen that we have provided a very simple and efficient bed which may be easily adjusted to any desired position by an occupant or may be completely folded when not in use.

The device will be found of especial value to hospitals, but may, of course, be advantageously employed in private homes.

What we claim is:—

1. A folding bed comprising a main frame, a head frame pivotally attached thereto at one side, a foot frame pivotally attached to the opposite side of the main frame, and a bed bottom having a portion secured to the head frame and its remaining portion movable on and supported by the foot frame.

2. A folding bed comprising a main frame, a foot frame pivoted thereto at one side, a head frame pivoted to the opposite side of the main frame, a bed bottom having

70

its foot end movable and supported upon the foot frame, and connections between the head frame and the foot portion of the bed bottom whereby when the head frame is 5 raised the bed bottom will be folded and its free end caused to travel upon the foot frame.

3. A folding bed comprising a main frame, a foot frame pivoted to one side of 10 the main frame, a track at the outer end of the foot frame, a bed bottom arranged at one end to travel on said tracks, and a head frame pivotally mounted upon the main frame and connected with the bed bottom.

15 4. The combination of a main frame, a foot frame pivoted thereto, a head frame comprising upper and lower bars pivoted to the main frame, a bed bottom having side bars movably supported at their outer ends

20 on the foot frame, intermediate bars connecting said side bars with the upper side bars of the head frame, and levers pivoted to the lower side bars of the head frame and to the said intermediate bars.

25 5. The combination of a main frame, a foot frame consisting of upper and lower side bars pivoted to the main frame, and supplemental legs pivoted to the outer ends of said upper and lower side bars, a foot- 30 plate rigid with the outer ends of the upper side bars, inclined tracks secured to the foot-plate and the said upper side bars, and a foldable bed bottom having its head-portion supported upon the main frame and its free 35 foot end traveling upon said tracks.

6. The combination of a main frame, a head frame pivotally attached thereto and extending therefrom, and tension springs secured at their inner ends to the main 40 frame and at their outer ends to the outer end of the head frame near the bottom thereof.

7. The combination of a head frame, a head-board detachably engaging the head 45 frame, and lever arms pivoted upon the head frame and having a pivotal connection with the said head-board.

8. The combination of a head frame, lever arms pivoted upon the sides of the head

frame, a pivot rod carried by the outer ends 50 of said lever arms, a head-board hung upon said pivot rod, and stops upon the lever arms adapted to support said head-board.

9. The combination of a main frame, a foot frame extending therefrom, a bed bottom 55 having a rolling support on said foot frame, and means for folding or extending said bed bottom.

10. The combination of a main frame, a head frame pivoted to one side of the main 60 frame and extending inwardly from said side of the main frame, a foot frame pivoted to the opposite side of the main frame, a foldable frame pivoted to the upper portion of the head frame and extending over the 65 foot frame, and connections between said foldable frame and the lower portion of the head frame.

11. The combination of a main frame, and an extensible frame balanced thereon, said 70 frame being adapted to project laterally beyond the opposite sides of the main frame or to be wholly or partly collapsed above the same.

12. The combination of a main frame, a 75 foldable frame extending over and projecting beyond the opposite sides of the main frame and having a portion pivoted to the main frame, and means for holding the foldable frame in a partly or wholly collapsed position.

13. The combination of a main frame having four posts or legs, two of which extend upward a distance above the main frame and having the side bars of the head 85 section of the bed bottom pivotally attached to the upper extremities thereof, the foot section of the bed bottom being supported on rollers which run on tracks in such a way that the bed bottom becomes balanced 90 on said pivoted points.

In testimony whereof we affix our signatures in presence of two witnesses.
